APPARATUS FOR APPLYING LIQUID POISON
TO PLANTS

Alex M. Corley, Salley, S. C.

Application October 11, 1937, Serial No. 168,459

5 Claims. (Cl. 299—30)

My invention relates to apparatus for applying liquid poison to plants.

An important object of the invention is to provide apparatus of the above mentioned character, which is adapted to apply a liquid insecticide to the cotton plant, for destroying the boll weevil, and which apparatus will apply the poison, to a considerable extent, to the undersides of the leaves and branches.

10 A further object of the invention is to provide apparatus of the above mentioned character which will bend the cotton plant forwardly, by engaging its top, without breaking or injuring the same, to permit of applying the poison to the 15 under side of the leaves.

A further object of the invention is to provide apparatus of the above mentioned character which will feed the liquid poison by gravity, in a highly efficient manner, to the absorbent element or mop.

A further object of the invention is to provide apparatus of the above mentioned character which may be conveniently flushed for cleaning the same.

25 A further object of the invention is to provide apparatus of the above mentioned character which is in the nature of an attachment to be mounted upon the beam of the plow or cultivator.

A further object of the invention is to provide 30 apparatus of the above mentioned character which is both vertically and horizontally adjustable.

Other objects and advantages of the invention will be apparent during the course of the following description.

In the accompanying drawing forming a part of this application and in which like numerals are employed to designate like parts throughout the same,

40 Figure 1 is a perspective view of apparatus embodying my invention,

Figure 2 is a side elevation, parts in elevation, of the attachment embodying my invention,

Figure 3 is a plan view of the same, and,

45 Figure 4 is a vertical section through the lower portion of the flexible hose.

In the drawing, wherein for the purpose of illustration is shown a preferred embodiment of my invention, the numeral 5 designates the beam 50 of the plow or cultivator, equipped with the handle 6, as is well known.

55 My liquid applying apparatus is adapted to be installed upon the beam 5 and may be used when the cotton is being plowed or cultivated. My apparatus comprises a supporting bracket, which

is vertically and horizontally adjustable. This supporting bracket comprises horizontal and vertical tubes or pipes 7 and 8, connected by a T-coupling 9. Only one horizontal tube 7 is shown connected with one end of the T-coupling 9, but another horizontal tube may be connected with the opposite end of the T-coupling 9, when it is desired to support two apparatuses from the beam 5. The vertical tube 8 slidably receives a vertical rod 10, and the vertical tube 10 is adapted to be clamped to the rod 10 in the selected adjusted elevation by means of a set screw 11 or the like. The vertical rod 10 is rigidly attached to an inverted U-shaped clamp 12, which receives the beam 5 and may be held 15 thereon by a screw 13 or the like. The horizontal tube 7 slidably receives a horizontal rod 14, adapted to be clamped therein in the selected horizontal position, by a set screw 15 or the like. Rigidly attached to the free end of the horizontal rod 14 is a band 16, formed of strap iron or the like, and this band is preferably circular. The band has separated end portions or extensions 17, provided with outwardly bulging intermediate semi-circular portions 18. The extensions 17 20 are adjustably connected upon opposite sides of the bulging portions 18 by bolts 19, carrying thumb nuts 20. Band 16 and its extensions are 25 resilient.

The band 16 is horizontally arranged and receives therein a vertical preferably cylindrical tank or reservoir 21, having a cover 22, provided with a vent 22'. The tank 21 fits within the band 16 and is firmly held therein by frictional engagement, when the inner winged nut 20 is suitably screwed up. The tank 21 has a lower downwardly tapering bottom 23, the upper large end of which is covered by a strainer 24. At its lower end, the tapered bottom 23 has a tubular coupling 25, to receive thereon one end of a flexible 40 hose 26, clamped thereon by a ring 26'. This hose is bent upon itself into a general U-shape, providing vertical arms 27 and 28. The vertical arm 28 has its upper end held between the outwardly bulging portions 18 of the extensions 17. 45 By unscrewing the outer winged nut 20, the arm 28 may be removed from between the outwardly bulging portions 18. It is thus seen that the tank 21 and arm 27 form one arm of a U-shaped syphon, while the arm 28 constitutes the other 50 arm.

The intermediate curved or bent portion of the hose 26 carries an absorbent element or mop 29, surrounding the same, and having depending flexible absorbent elements or cords 30. A valve 55

or petcock 31 is attached to the outer arm 28 near and above the line of sediment 32 in the curved or bent intermediate portion of the hose 26. This valve or petcock is preferably inclined 5 and arranged near and above the body portion 29 of the absorbent element or mop, so that it discharges the liquid poison upon the body portion 29, as shown by the arrows.

The operation of the apparatus is as follows:

10 With the apparatus mounted upon the plow beam 5, as shown, the tank 21 is suitably filled with the liquid poison and the strainer 24 will prevent the passage into the hose 27 of large particles. Since the upper end of the arm 28 is 15 at all times open to the atmosphere, there is no tendency to create a vacuum in the U-shaped hose 26, and hence when the valve or petcock 31 is opened, the liquid will discharge freely from the petcock. The liquid poison passing upon 20 the upper or body portion 29 of the absorbent element is transmitted to the lower portion or cords 30 of the mop, which become saturated with the liquid. As the beam 5 is moved downwardly of the row of cotton, upon one side thereof, the U-shaped hose 26 engages the upper 25 end or top of the cotton plants, bending them forwardly without breakage, and this action is followed by the cords 30 of the absorbent element or mop, which will accordingly apply the 30 liquid poison, to a considerable extent, to the lower sides of the leaves of the plant. This is important, as it prevents the poison from being readily washed off by the rain. The valve or petcock 31 is located above the level of sediment, 35 indicated at 32. When it is desired to clean the hose 26 and tank 21, the upper end of the arm 28 is removed from between the outwardly bulging portions 18, which may be effected by unscrewing the outer winged nut 20. The arm 28 40 is then horizontally arranged and water may be poured through the tank 21 and hose 26, to flush and hence clean the same.

It is to be understood that the form of my invention herewith shown and described is to be taken as a preferred example of the same, and that various changes in the shape, size, and arrangement of parts, may be resorted to, without departing from the spirit of my invention or the scope of the subjoined claims.

50 Having thus described my invention, I claim:

1. An apparatus for applying liquid poison to cotton plants or the like, comprising a support, a tank mounted upon the support for receiving the liquid poison, a generally U-shaped conduit having spaced arms, one arm being connected with the tank and the other arm being open near its upper end, a flexible absorbent

liquid applying member carried by the transverse portion of the generally U-shaped conduit, and an outlet device connected with one of said arms and arranged to apply the liquid poison to the absorbent element.

2. An apparatus for applying liquid poison to cotton plants or the like, comprising a support, a tank mounted upon the support for receiving the liquid poison, a flexible hose connected with the tank and having its free end adapted to be 10 raised to an elevated position above its attached end, releasable means to hold the free end elevated, a flexible absorbent element mounted upon the hose, said hose having means for supplying the liquid poison to the absorbent element.

15 3. An apparatus for applying liquid poison to cotton plants or the like, comprising a support, a tank mounted upon the support for receiving the liquid poison, a flexible hose connected with the tank and having its free end adapted to be 20 elevated, releasable means for holding the free end elevated, the hose permitting of the tank being flushed when the free end of the hose is lowered, a flexible absorbent element mounted 25 upon the hose, and an outlet device connected with the hose and discharging the liquid poison at an elevation above the flexible element and upon the flexible element.

30 4. An apparatus for applying liquid poison to cotton plants or the like, comprising a support, a band secured to the support and having separate extensions serving as a hose clamp, a tank mounted within the band, a flexible hose connected with the lower portion of the tank and bent upwardly and having its free end portion 35 releasably held within the clamp, an absorbent flexible element mounted upon the transverse portion of the hose, and a valve connected with the hose near and above the absorbent element to supply the liquid poison to the absorbent element.

35 5. Apparatus for applying liquid poison to cotton plants or the like, a clamp to be mounted upon the beam of the plow or cultivator, a vertically and horizontally adjustable support 40 carried by the clamp, a tank mounted upon the support, a U-shaped conduit attached to the tank and extending laterally of the plow beam said conduit having its free end adapted to be arranged above its attached end, releasable means 45 for holding the free end of the conduit, a flexible absorbent element mounted upon the transverse portion of the conduit, said conduit having means for applying the liquid poison to the absorbent element.

50 ALEX M. CORLEY.
